RAILWAY SIGNAL LANTERN

John G. MacHutchin, Berwick, and Walter Frank Buck,
Bloomsburg, Pa., assignors to United States Radium
Corporation, Morristown, N.J., a corporation of Dela-
ware

Filed July 10, 1962, Ser. No. 70,861

Term of patent 14 years

(Cl. D48—24)

FIGURE 1 is a perspective view of a railway signal lantern embodying our new design, it being understood that the undisclosed sides are substantially the same in appearance as the sides shown in this figure;

FIGURE 2 is a top plan view thereof;

FIGURE 3 is a side elevational view thereof; and

FIGURE 4 is a bottom plan view thereof, partly broken away.

We claim:

The ornamental design for a railway signal lantern, as shown and described.
